UNITED STATES PATENT OFFICE.

GIANNI CAPRONI, OF MILAN, ITALY.

FLYING-MACHINE CONSTRUCTION.

1,416,167.

Specification of Letters Patent. Patented May 16, 1922.

Application filed April 22, 1919. Serial No. 292,001.

To all whom it may concern:

Be it known that GIANNI CAPRONI, engineer, subject of the Kingdom of Italy, residing at Milan, Via Durini No. 24, Italy, 5 has invented certain new and useful Improvements in Flying-Machine Constructions, of which the following is a specification.

The invention relates to improvements in 10 flying machine constructions and particularly refers to multiplanes having for its object to reduce the resistance of the air against the front cell or wing during flight.

With this object in view, the invention 15 consists in the new arrangement of the cables wherein the purpose is to maintain only the diagonal cables in the structure of the cell.

The object of the invention will be better 20 understood with reference to the annexed drawing giving, by way of example, a form of the construction of the invention as applied to the triplane.

Fig. 1 is a front view of an aeroplane, 25 showing the arrangement which constitutes the invention.

Fig. 2 is a perspective view of central junction means connected with the invention.

Fig. 3 is a plan view of the means as 30 represented in Fig. 2.

Fig. 4 is a side sectional view of the same means.

Similar characters of references designate 35 corresponding parts throughout the several views.

Referring now more particularly to the accompanying drawings there is provided a triplane of the knock-down type including 40 the front central cell 1 which has detachably connected thereto the side cells or wings —2—2'—, one of the latter being shown disconnected for the purpose of clarity. These cells or wings comprise longitudinals 45 —3—3'— and 3''— connected at suitable intervals by uprights 4.

Cables 5—5'— are provided while a central junction piece 6 is employed to receive one of the ends of each of said cables.

50 A fuselage 7 is connected with the front cell and in turn has connected thereto a landing carriage 8. The lateral cells or wings —2—2'— are symmetrically connected to the central cell —1— while the longitudinals are tied to one another by means

of the uprights 4 and diagonal cables —5— so as to form a rigid and resistive structure.

The cables —5'— stretched between points —9— and the upper ends 10 of one of the 60 uprights 4 gives the side cells or wings the necessary horizontal stability.

The central junction piece —6— consists of a tie —11— journalled and fastened on the medial longitudinal —3'— each tie being 65 provided with a hemispherical casing 12 which is kept in place by a flange 13 resting on the longitudinal and embraced by the turned down rand or flange 15 of the said tie. 70

This latter construction is such that the casing may be turned and the casing is in turn provided with radial holes —15— which receive nipples —14— the heads 15 of which are anchored within the casing 12 75 while the outwardly projecting portions of the nipples are threaded internally for receiving the corresponding threaded adjacent ends of the diagonal cables —5—. The casing is further provided with hole 80 —16— for giving passage to the uprights 4.

Having now particularly described the nature of my invention and the manner in which the same should be performed, I claim:— 85

1. An aeroplane structure comprising a plurality of superposed planes including a plurality of longitudinals, a plurality of uprights extending vertically from one longitudinal to the other, a plurality of staywires extending between the ends of said uprights and crossing each other in groups on points of the medial longitudinal, a hemispherical casing having its base connected to said medial longitudinal, and means for connecting the staywires to the casing. 90

2. An aeroplane structure comprising a plurality of superposed planes including a plurality of longitudinals, a plurality of 100 uprights extending vertically from one plane to the other, a plurality of staywires extending between said uprights and crossing each other in groups on points of said longitudinals and said uprights, hemispherical casing having a flanged base fitted against the medial longitudinal, a stirrup surrounding the medial longitudinal and embracing the flanged base so as to permit 105 of turning of the casing, said stirrup being 110

fastened on a longitudinal in proximity of an upright, and headed nipples anchored in said casing to receive the adjacent ends of said staywires.

5. 3. In a structure as claimed in claim 2 wherein the casing is provided with a large central opening to give passage to the upright and further provided with a circle

of holes in which the headed nipples are anchored.

In testimony whereof I affixed my signature in the presence of two witnesses.

GIANNI CAPRONI.
